UNITED STATES PATENT OFFICE.

PETER C. GREENAWALT, OF READING, PENNSYLVANIA.

SAD-IRON.

SPECIFICATION forming part of Letters Patent No. 787,289, dated April 11, 1905.

Application filed July 18, 1904. Serial No. 217,047.

REEDSBURG

To all whom it may concern:

Be it known that I, PETER C. GREENAWALT, a citizen of the United States, residing at Reading, in the county of Berks and State of Pennsylvania, have invented certain new and useful Improvements in Sad-Irons; and I do hereby declare the following to be a full, clear, and exact description of the invention, such as will enable others skilled in the art to which it appertains to make and use the same.

This invention relates to improvements in sad-irons.

The object of the invention is to improve the construction of means for removably securing the handle of the iron of this class in an assembled position with the body thereof.

Another object of the invention is to provide a removable handle with cushioned locking means whereby said handle may be securely assembled with the body portion of an iron.

A still further object of the invention is to construct an iron with a removable handle and to assemble with said handle movable locking means, which is provided with flexible means for positively retaining said handle in an assembled position with the body portion of the iron.

With these and other objects in view the invention consists in certain novel constructions, combinations, and arrangements of parts, as will be hereinafter fully described, illustrated in the accompanying drawings, and more particularly pointed out in the claims hereto appended.

In the drawings, Figure 1 is a view in side elevation of an iron constructed in accordance with the present invention, shown partly in section. Fig. 2 is an inverted plan view of the handle, showing the fastening means carried thereby in an unlocked position. Fig. 3 is a plan view of the body portion of an iron constructed in accordance with the present invention. Fig. 4 is a plan view of the handle, showing the fastening means carried thereby in a locked position.

In carrying out the present invention I employ a sad-iron having a body portion 1 of any preferred construction, which is provided with an upper or top portion 2, which is in-

tegrally secured to the body portion 1. The top portion 2 can be cast with the body portion 1 if it is desired. A central opening 3 is formed in the top 2 of the body of the iron. Said opening 3 is preferably elliptical in construction, although this particular feature of the invention may be departed from in constructing a complete device without materially affecting the spirit and scope of the present invention. A plurality of openings 4, 55 preferably elliptical in shape, is formed upon the top of the body portion diametrically in opposite positions to the central opening or aperture 3. The openings 3 and 4 communicate with a compartment formed in the body 60 portion of the iron.

The handle comprises in its construction a base or bottom portion 5, which is provided near each end with integral apertured annular extension 6, 6, to which the end portions of the handle are secured. The handle 7 is secured to base 5 by means of screws 8, 8, which are positioned within recesses 9 formed in the base portion near the ends thereof. Said screws are passed through the 70 apertured portion of integral extensions 6 and into the handle 7. The handle 7 is preferably constructed of wood or some other non-conductive material.

Upon the bottom of base portion 5 of the 80 handle there is formed a plurality of integral extensions 10, which are positioned upon said portion 5 so as to enter the apertures 4, 4 of the top of the base 1 of the iron when said handle and base are assembled. A plurality 85 of openings 11 are formed upon opposite sides of the central aperture or opening 13^a, through which the post of the fastening device is adapted to be passed when the same is assembled with said handle. A plurality of recesses 12, 90c 12 are formed upon the upper surface of the base portion 5 of the handle.

The fastening mechanism, which is assembled with the handle for retaining the same in a fixed assembled position with the body portion, comprises in its construction a post 13, which is positioned within the central aperture 13^a, formed in the base 5 intermediate of openings 11, 11. The post 13 is provided with an integral right-angled extension 14, which 100

is preferably constructed elliptical in shape for the purpose of permitting of passage thereof through central opening 3 when it is desired to assemble the handle with the body portion. The head or extension 14 is secured at one end of the post 13, and near the opposite end thereof there is secured a lever-arm 15, which is provided with an integral lug 16 upon the lower face thereof and with an extension 16^a upon the upper face. A grip 17 is preferably mounted upon right-angled extension 16^a of the lever-arm 15, said grip being constructed of non-conductive material. The post or shank 13 is of greater length than the thickness of the base 5, permitting of a slight vertical movement thereof through the central opening when assembled in its normal position with base portion 5. Mounted upon the shank or post 13 is a flexible, angular member 18. The angular member 18 is preferably a flat, bowed spring, which is formed by bending a strip of material intermediate its ends, for the purpose of exerting an upward pressure at all times against the bottom portion 25 of lever-arm 15 when in an assembled position with the handle and the coacting parts of the fastening mechanism. The ends of spring 18 are notched at 19 upon each side thereof, said notched ends adapted to extend into the recesses 12 for the purpose of preventing lateral movement of said flexible member. The flexible member 18 provides cushioning means for the head 14, permitting of the same to be positioned within the compartment 35 formed in the body portion of the iron and positively retained in a locked or an unlocked position. The spring member 18 is of sufficient strength to bind the upper portion of the head or extension 14 at all times against the inner surface of the top or upper portion 40 of the body portion 1 of an iron. The manipulator of the device can easily operate the locking mechanism, owing to the simple construction thereof. The construction of the cushioned head insures of the retention of the handle in an assembled position with the body irrespective of the fact that the head may not be positioned at right angles to the base portion 5, as illustrated in Fig. 4, for if only a portion of 45 the head engages the inner surface of the top 2 it will be sufficient to retain the parts in an assembled position by reason of the cushioning member exerting an upward pressure on the head, and thereby binding the same against the engaging surface of the body 1. The operator of the device can easily engage the grip 17 with one finger without the liability of injury by reason of the lever-arm 15 becoming heated. The integral lug 16 limits the rotary movement 50 of the lever-arm 15. By turning the lever-arm either to right or left until the extension 16 engages one side of spring 18 the head 14 will be positioned, such as will permit of the handle to be removed from the body portion or positively retained in a locked po-

sition therewith when assembled with the same.

Although I have described the preferred form of the locking mechanism carried by the handle and have also described the construction of said handle, it will be obvious to one versed in the art to which this invention relates that certain deviations may be made in the construction of the turning post, its head, and operating member, together with the 70 cushioning means as well as the construction of the body portion of the iron for the purpose of permitting of the assembling therewith of a handle provided with a locking mechanism, and I therefore reserve the right to make 80 any alterations, modifications, and changes as shall fairly fall within the scope of the present invention.

Having thus fully described my invention, what I claim as new, and desire to secure by 85 Letters Patent, is—

1. A device of the character described, comprising a body portion having a compartment formed therein, said body portion having an opening communicating with said compartment, a handle assembled with said body portion provided with a fastening mechanism carried by the base thereof, comprising a post, a head secured near one end of said post upon one side of said base, a lever-arm secured to 95 said post near the opposite end thereof, and a bowed flexible member mounted upon said post intermediate of said lever-arm and base, said head being adapted to be positioned within the opening of said body for retaining said 100 handle in an assembled position with the body.

2. A device of the character described, comprising a body, a handle secured thereto, of a locking mechanism carried by said handle, comprising a movable member, a head secured 105 near one end of said member, lever means secured to said member near the opposite end, an integral lug projecting from said lever means for limiting the movement of said member, and a bowed spring surrounding said 110 movable member intermediate its length and positively secured to said handle.

3. In a device of the character described, the combination of a body having a top, said top provided with a plurality of apertures, a 115 handle removably mounted upon said body, comprising a base portion, a removable arched member secured to said base portion, said base portion having a central aperture and a plurality of recesses formed upon its upper surface, a post journaled in said central apertured portion, a head secured to said post near the lower end thereof, a lever-arm secured to the opposite end of said post, said arm comprising a body portion provided with extensions projecting therefrom upon opposite sides thereof, a grip carried by one of said extensions, an approximately flat spring bowed intermediate its ends and having notched end portions mounted upon said post adjacent to 120

said arm, said notched ends normally projecting into the recessed portions of said base of the handle, and a plurality of integral extensions projecting from the lower surface of said base and normally engaging part of said apertures formed in the top of said body.

4. In a device of the character described, the combination with a body, of a handle provided with a face portion positioned thereon, locking means carried by said handle, comprising a revolute member, a head secured to said revolute member, lever means secured to said revolute member, an angular spring positioned upon said revolute member between said lever means and base portion of the handle, and means formed upon the lever means adapted to engage said spring for limiting movement of said revolute member.

5. In a device of the character described, the combination with a body, a handle positioned thereon, of locking means carried by said handle, comprising a revolute member, a head secured to said revolute member, lever means carried by said revolute member, cushioning means assembled with said revolute means and handle, and means carried by said lever means adapted to engage said cushioning means for limiting movement of said revolute member.

6. In a device of the character described,

the combination with a body, a handle positioned thereon, of locking means for securing said handle in a positive assembled position with said body, comprising a revolute member carried by said handle, a lever-arm secured to said member, a head formed upon said member, flexible means positioned upon said handle for normally holding the head of said revolute member in a positive engaging position with said body, and means extending from said lever-arm adapted to engage said flexible means for limiting movement of said revolute member.

7. The combination with a body, a handle removably positioned thereon, of a locking mechanism carried by said handle, comprising a movable member, a head secured near one end of said member, an arm mounted upon the opposite end of said member, flexible means interposed between said arm and handle, and means carried by said arm adapted to engage said flexible means for limiting movement of said member and its head.

In testimony whereof I hereunto affix my signature in presence of two witnesses.

PETER C. GREENAWALT.
